CARBURETING DEVICE

Yessimir Djordjevitch, Paris, France

Application October 23, 1935, Serial No. 46,396
In France October 24, 1934

5 Claims. (Cl. 261—41)

The devices used as atomizers in carbureters generally provide the internal combustion motors with a fuel or mixture lacking proper homogeneity and which is thereby detrimental to the proper 5 economical operation of the motor.

My invention has for its object a novel device the arrangement of which allows the production of a mixture suited for each speed of the motor and providing the most economical operation 10 possible.

This novel device provides for an equal size a much greater contact area between the air and the fuel and thus it is possible to obtain a very light perfectly homogeneous mixture which is the 15 essential condition for a proper carbureting.

Moreover the direction and the special shape of the ports through which the mixture passes out of atomizing chamber are such as will give the gaseous streams passing out of the ports shapes approximating that of the space left open 20 by the throttle valve as it opens and moves away from the walls of the duct enclosing it. The current of aeriform mixture is thus divided and passes through the two openings provided on either side of the throttle valve, which prevents 25 any substantial loss of pressure in the main admission channel to the carbureter and also any substantial condensation as generally produced by the impinging on the axis of the throttle valve and on the throttle valve itself. To this end, the 30 atomizer according to my invention constrains the fuel to pass through ports provided at a certain distance from the center of one of the opposite walls of a mixing chamber along two arcs on either side of a diameter parallel to the pivoting axis of the throttle valve, said passage of fuel 35 being performed under the action of the air sucked into said chamber through openings provided in front of the just mentioned ports in the opposite wall of the chamber.

Moreover it is possible to choose the relative size of the admission parts for the air or other oxidizing aeriform fluid with reference to the size of the outlet ports for the mixture and also the height and volume of the atomizing chamber so 45 as to obtain an automatic measure of the admission of air either through an acceleration of the flow of air through said chamber or through a braking thereof.

It is in fact possible to accelerate this flow of air on one side of the atomizing chamber and to brake it on the other side in order to make the force of the jet of mixture correspond with the position and shape of the throttle valve or the like part closing the main admission pipe. It is 50

also possible to permanently accelerate or brake the outlet of the mixture on one side of the chamber and to provide on the other side a mixed flow i. e. a flow which is accelerated or braked according to the speed of the motor. 5

Eventually, part of the atomizer may be of a substance different from the remainder of the atomizer, in particular as far as conductibility is concerned.

The operation of the atomizer allows its use 10 alternately as an idling atomizer and as a main atomizer, the motor being constrained to suck the mixture, according to the degree of opening of the throttle valve, either from one or from the other side of the atomizer. 15

I have shown by way of example in accompanying drawings a certain number of forms of execution of the invention:

Fig. 1 shows a carbureter the main spray nozzle of which is constituted by one of my improved 20 atomizers,

Fig. 2 shows the atomizer seen from above,

Figs. 3 to 11 are longitudinal cross-sections of different modifications,

Figs. 12 and 13 show two modifications of a 25 reversed carbureter to which the invention has been applied,

Fig. 14 is a modification of Fig. 2,

Figs. 15 and 16 are a view from above and a cross section of an atomizer of the type shown in 30 Fig. 2 with the addition of vibratory blades,

Fig. 17 is a modification thereof,

Figs. 18 and 19 show an atomizer as disclosed 35 serving in alternation as an atomizer for idling (Fig. 18) and as a main atomizer (Fig. 19).

The carbureter of Fig. 1 is a normal carbureter comprising a main spray nozzle 1 connected with the float chamber 2 through the channel 3 and the calibrated plug 4, and an idling spray nozzle forming a branch of the same channel. The 40 idling spray nozzle is shown in this case as an ordinary atomizer projecting the fuel axially into the fuel diffusing part 20 of the pipe 21 in which the air enters through the channels 14—18—19 under the action of the suction of 45 the motor. On the contrary the main spray nozzle comprises an atomizer designed according to the invention and the body 6 of which is provided with a central channel 9 opening into a mixture chamber 8; the upper wall 7 of this 50 chamber is provided at its periphery with perforations 11 arranged along two arcs of a circle on either side of a diameter (Fig. 2). These perforations may show any suitable shape and appear in particular as a crescent or a bean on 55

either side of a diameter of the chamber. The lower wall of the chamber is provided with smaller corresponding ports 10 which are thus on the outside of the wall of the channel 9. The 5 lower end of the channel 9 of the atomizer is held against the outlet of the fuel feeding channel 3 by a sleeve 12 screwed into the casing 1 of the spray nozzle so as to form round the atomizer a vacant space 15 communicating on one hand 10 through the openings 16 in the wall of the sleeve with the channel 14, through which air is admitted and on the other with the ports 10 of the atomizer mixture chamber.

It is apparent that the air, pure or already 15 emulsified, hot or cold, forced under pressure or sucked by the motor, passing through 14, 16, 15, 10 enters the mixture chamber 8 which is preferably half immersed in fuel. The air entering said chamber sucks the fuel arriving 20 through 3 and 9 and forms with it a mixture which passes into the chamber 17 directed towards the throttle valve 13, through the annular series of perforations 11 whereby the mixture has a tendency to impinge only on the crescent- 25 shaped open spaces between the open throttle valve 13 and the wall of the pipe containing it, without substantially touching the central portion of the throttle valve nor the axis round which it pivots, said portion and axis obviously 30 not requiring any mixture. The shape of the superposed air admission ports 10 and mixture outlet ports 11 in the mixture chamber is apparent from Fig. 2. The ports 11 being larger than the ports 10, the mixture expands as it 35 passes out of the chamber.

Fig. 3 shows a modification in which the sleeve 12 is provided with a supplementary air admission at 22 beyond the outlet for the mixture out of the mixture chamber.

40 It is of course possible to use for the idling spray nozzle the just described arrangement with its annual projection of the mixture. The main spray nozzle is in this case either of the conventional type or of the above described type. 45 Moreover the improved atomizer may be used with advantage in auxiliary starting carburetors or so-called starters.

Fig. 4 shows an atomizer adapted for idling, in which the outlet ports of the mixture chamber 50 are smaller than the inlet ports so as to increase the braking on the flow of fuel when the suction increases.

Fig. 5 shows an atomizer of the type shown in Fig. 1 for the main spray nozzle, wherein the 55 two portions of the mixture jet passing through the two arcs of a circle 10 are separated by a partition 24 dividing the chamber 8 into two half-chambers. Fig. 6 shows an atomizer similar to that of Figs. 1 and 2 except in that one part or system of ports 11' only is larger than the corresponding port or system of ports 10', the 60 ports 10'' and 11'' on the other side of the chamber being of equal size.

In the atomizer of Fig. 7, the apertures 10³ and 10⁴ are respectively smaller and larger than the corresponding apertures 11³ and 11⁴.

The atomizer of Fig. 8 is similar to that of Figs. 1 and 2 with the addition of a supplementary air admission port 25 opening into the central fuel channel 9.

Fig. 9 shows an atomizer in which the ports 10 are equal in size to ports 11.

Fig. 10 shows an idling atomizer, the corresponding ports 10 and 11 on one side being

equal, while the port 11 on the other side is smaller than the corresponding port 10.

Lastly in Fig. 11, there is shown an atomizer in which the opposite walls of the mixture chamber are no longer parallel to one another but are 5 at an angle one with another whereby the wall facing the throttle valve may be parallel to one of the positions taken by the throttle valve when open. At the same time the difference between the travel distances of the fluid at both sides of 10 the mixture chamber has for its result a favorable modification in the balance of the flow of the fuel through its outlet ports.

Of course, the shape of the peripheric apertures may be modified in the widest variety of 15 manners. In particular, instead of forming an entire arc of a circle, they may, chiefly in the lower wall, be distributed along this arc of a circle under the shape of a series of circular apertures, which may be independent or else have 20 portions common to two successive apertures. Fig. 14 shows a modification of Fig. 2 wherein the apertures are no longer bean shaped, but have a crescent shape similar to that of the crescents formed by the passages uncovered by 25 the throttle valve when it is opened and moves away from the walls of the duct enclosing it. It will be noticed that the number of arcs of a circle corresponding to ports or systems or ports is not necessarily two and may be reduced to 30 one or increased above two.

Fig. 12 shows the spray nozzles of a reversed flow or downflow carburetor. The main spray nozzle has an atomizer arranged as precedently in a chamber opening into a restricted portion 35 of the admission pipe just before the throttle valve. Of course, the smaller openings 10 are provided in the upper wall of the chamber and the larger openings 11 in the lower wall. Preferably the fuel is caused to arrive in this case 40 laterally into the chamber 8 through the small pipe 26. But it is possible to use in this case of downflow carburetors as in the case of normal carburetors, either an atomizer with an axial admission of fuel or an atomizer with a lateral 45 admission of fuel.

The auxiliary atomizer of Fig. 12 is of the type of Fig. 4 but with the openings reversed, whereas the downflow carburetor of Fig. 13 comprises an auxiliary atomizer of the conventional type. It 50 is of course possible to use in combination a conventional main spray nozzle with an auxiliary nozzle according to the invention.

In the atomizer of Figs. 15 and 16, a vibratory blade is placed in the atomizing or mixture 55 chamber, between the admission port for the emulsifying air and the outlet ports for the mixture.

This blade has for its effect to stir the mixture forming in the atomizing chamber 9 through its 60 vibrations produced by the air sucked in. The vibratory blade may be used with all forms of execution of the invention. It may moreover appear under any other suitable shape and be placed in the chamber 8 in any manner suitable 65 for the result sought for, for instance flat or on edge, lengthwise or breadthwise.

Fig. 17 shows another modification wherein the ports 10 and 11 depart from the shape shown in Fig. 2 and appear as the chord of the arc previously formed by them and straight vibratory blades may in this case be set along their centre lines as shown.

Figs. 18 and 19 illustrate an application of the atomizer according to invention and working as 75

a depression controlling means, acting in alternation as a main atomizer and as an idling atomizer.

In Fig. 18, the atomizer described works as an idling device because, the throttle valve A being closed, the depression of the motor is applied on the outlet channel B and consequently on the annular space F surrounding the body of the atomizer 6 and therefore there is produced a suction of the fuel which enters the chamber 8 through the central channel 9. This fuel passes out through the ports at the same time as the air entering through the ports 11. The fuel thus partly admixed with air passes out into the space F wherein the mixture is completed by the air coming from the channel 14 and thence into the motor through the pipe G and the outlet channel B opening into the main admission pipe.

When the motor is accelerated, the throttle valve A is opened and the depression which was first zero ahead of the throttle valve increases and begins causing a suction on the outlet ports 11 and as this depression acts more and more above the atomizer, the fuel passes more and more through the ports 11; at a given moment, the air advancing towards the pipe C through the channel 14 changes its direction and begins passing partly through the normal admission ports 10 which are smaller than the ports 11, into the mixture chamber 8. The air then carries along with it the fuel and mixed therewith passes out through the ports 11 towards the motor as illustrated in Fig. 19.

The consequence of this manner of working is that at a certain moment the depression in the motor becomes large enough above the atomizer for the air coming from the channel 14 to pass through the ports 10 and to draw violently with it through the outlet ports 11 all the fuel entering the chamber through the central passage 9; consequently the idling mixture is no longer sucked and the fuel can pass no more through the channel C until the throttle valve is returned towards its closed position. The depression, still very strong, acts then on the ports 10, but with a strength such that the air hits the opening of the passage 9 and prevents the fuel from passing through. It is only when the speed of the motor has fallen to idling speed that the fuel is sucked out of the channel 9 and is admixed with the air passing through the pipe C into the motor. The cycle of operations begins over again and the mixture the direction of which has changed causes now the motor to rotate at idling speed.

A single calibrated aperture D provides the fuel for the atomizer both for idling and for normal speed operation of the motor.

In case of need, it is possible to modify the richness of the mixture for idling purposes by a suitable device disposed at e, such as a suitably controlled air admission port.

Obviously without widening the scope of the invention, it is possible to modify in any desired manner the shape of the inlet and outlet ports for the gases into the atomizer as well as the general shape of the atomizers described. These may also be executed in any suitable material according to their intended use for forming a homogeneous mixture of a liquid with a gas or a vapour which it is desired to project in one

or more predetermined directions. In any case, it is possible to combine in any suitable manner the different arrangements disclosed hereinabove.

What I claim is:

1. In an atomizer for liquid fuel adapted to be submitted to suction from the admission pipe of a motor including a pivoting throttle valve, the provision of a closed mixture chamber the axis of which is directed towards the throttle valve 10 provided with two opposite thin flat solid walls, ports being arranged near the periphery of each of said walls solely along two diametrically opposed portions of said wall to either side of a diameter parallel to the pivoting axis of the 15 throttle valve, the ports in one wall lying in front of the ports in the other and an admission duct for the fuel being provided through the center of one of said walls.

2. In combination with an atomizer as claimed 20 in claim 1, means for leading air to the outside of both opposite walls of the mixture chamber selectively according to the degree of throttling in the admission pipe, said means urging the fuel back into its admission duct when the suction in the throttled pipe is above idling value.

3. In an atomizer for liquid fuel adapted to be submitted to suction from the admission pipe of a motor including a pivoting throttle valve, the provision of a closed shallow cylindrical mixture chamber the axis of which is directed towards the throttle valve provided with two opposite thin flat walls forming the top and bottom thereof, elongated port systems symmetrically arranged in each wall to either side of a diameter 30 parallel to the pivoting axis of the throttle valve towards the periphery thereof, the ports in one wall lying in front of the ports in the other and means for admitting the fuel into said chamber.

4. In an atomizer for liquid fuel adapted to be submitted to suction from the admission pipe of a motor fitted with a pivoting throttle valve, the provision of a closed shallow cylindrical mixture chamber, the axis of which is directed towards the throttle valve provided with two opposite thin flat walls, ports being arranged along separate arcs of a circle formed on either side of a diameter parallel to the pivoting axis of the throttle valve near the periphery of each of said walls for the admission of air and the projection of the mixture of air and fuel respectively, the ports in one wall lying in front of the ports in the other, means for admitting the fuel into said chamber and vibratory blades arranged in the ports.

5. In an atomizer for liquid fuel adapted to be submitted to suction from the admission pipe of a motor including a pivoting throttle valve the provision of a closed mixture chamber the axis of which is directed towards the throttle valve provided with two opposite thin flat solid walls, the wall facing the throttle valve being oblique with reference to the axis of the chamber, ports being arranged near the periphery of each wall solely along two diametrically opposed portions of said wall to either side of a diameter parallel to the pivoting axis of the throttle valve, the ports in one wall lying in front of the ports in the other and an admission duct for the fuel being provided into said chamber.

YESDIMIR DJORDJEVITCH.
